O. PETERSEN

DAMPER CONTROL

Filed April 17, 1924

Inventor:

Oscar Petersen,
By Syrenforth, Jr., Clinton Miles,
H. D. G.

UNITED STATES PATENT OFFICE.

OSCAR PETERSEN, OF CHICAGO, ILLINOIS, ASSIGNOR TO MILLS NOVELTY COMPANY,
OF CHICAGO, ILLINOIS, A CORPORATION OF ILLINOIS.

DAMPER CONTROL.

Application filed April 17, 1924. Serial No. 707,113.

This invention relates to damper control mechanism for use in player pianos and the like and is fully described in the following specification and shown in the accompanying drawing in which the figure is a partial end elevation of a player action showing the control magnets for the dampers.

The device as illustrated is adapted to be used on a player piano or the like of the type shown and described in the patent to Henry K. Sandell, No. 1,603,871, granted October 19, 1926, and comprises a frame 10 adapted to be secured to the string plate 11 of a piano, and on which is mounted an electro-magnet 12 having a horizontally movable core 13 of soft iron or the like.

A link 14 is pivotally connected at one end to the core 13 by means of a pin 15 and at the opposite end to the lower end of the lever 16 by means of a pin 17. This lever is pivotally mounted at its upper end and as it moves back and forth operates the damper mechanism (not shown) in the same way as in the above-mentioned patent to Sandell.

A pawl 18 pivotally mounted at 19 has a shoulder 20 adapted to drop behind the pin 21 on the lever 16, which is preferably covered with felt. These parts are so related that the pawl 18 drops behind the pin 21 when the lever 16 is drawn back by the electro-magnet 12 to the position shown.

The pawl 18 has an arm 22 which serves as an armature for the electro-magnet 23. When this electro-magnet is energized, the pawl 18 is retracted and the lever 16 is moved as by gravity, toward the electro-magnet 12, the lower edge 18^a of the pawl 18 resting upon the pin 21.

Thus it will be seen that with the parts in normal position, the lever 16 and core 13 are retracted and the edge 18^a of the pawl 18 rests upon the pin 21, and the damper (not shown) is in contact with the string. Energizing the electro-magnet 12 draws the core 13 to the left, forcing the lever to the position illustrated and raising the damper. The pawl 18 then drops behind the pin 21 and re-

tains the lever in this position until the electro-magnet 23 is actuated, thereby releasing the lever 16 and permitting it to return to its normal position whereby the damper is again in contact with its strings. Felt 23^a is placed on the end of the electro-magnet 23 which serves to deaden the sound and also assists in releasing the armature 22 when the electro-magnet 23 is de-energized.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to claim all novelty inherent in my invention as broadly as possible in view of the prior art.

I claim:

1. In a stringed instrument, a damper control lever, means for moving said lever to apply the damper, a latching-pawl having a shoulder adapted to engage a member on said lever and hold the lever in damping position, and an electro-magnet for lifting said pawl to release said lever.

2. In a stringed instrument, a damper-applying lever, an electromagnet serving to move said lever to apply the damper, a pivoted latching-lever adapted to automatically latch said first-named lever in damping position after the damper has been applied, and a second electro-magnet adapted to retract said latching-lever.

3. In means of the character set forth, a damper-actuating lever provided with a latching-shoulder, an electromagnet having a core linked to said lever and serving to secure it to the damping position, a pivoted latching-pawl operative to engage said shoulder and releasably hold said first-named lever in damping position, and a second electro-magnet adapted to retract said latching-lever.

OSCAR PETERSEN.
